RAILWAY TRAFFIC CONTROLLING APPARATUS

Filed May 16, 1939

UNITED STATES PATENT OFFICE

2,208,436

RAILWAY TRAFFIC CONTROLLING
APPARATUSMills Roger Snyder, Norfolk, Va., assignor to The
Union Switch & Signal Company, Swissvale,
Pa., a corporation of Pennsylvania

Application May 16, 1939, Serial No. 273,974

8 Claims. (Cl. 246—219)

My invention relates to railway traffic controlling apparatus.

One object of my invention is to provide novel and improved means for operating a railway traffic controlling device such as a passing siding switch, or the switch at the end of a double track, by governing the speed of a train approaching the switch, whereby an engineman may select the route over which he wishes to proceed without necessitating the stopping or substantial delay of his train.

Another object of my invention is to accomplish the aforementioned object with the same degree of efficiency and safety as would be provided if the switch were operated by a manually controlled power operated means.

I shall describe one form of apparatus embodying my invention, and shall then point out the novel features thereof in claims.

The accompanying drawing is a diagrammatic view showing one form of apparatus embodying my invention for causing the operation of a railway switch when a car approaching the switch passes over a given track section in greater than a predetermined time interval.

In the drawing in a number of instances one or more of the contacts of certain ones of the relays or devices are shown separated from the relays or devices themselves in order to enable the different circuits to be more readily followed. In each instance, each contact is given a reference character comprising a distinguishing number preceded by a dash and the reference character for the relay or device by which the contact is operated, and the contact is shown in the position corresponding to the normal condition of the relay or device. For example, the reference characters GPS—1 and GPS—2 applied to two of the contacts in the circuit for relay 3WR indicate that the associated contacts are the contacts 1 and 2 of relay GPS, and these contacts, being front contacts, are shown open since relay GPS is normally deenergized.

Referring to the drawing, a stretch of track X over which traffic normally moves in both directions is connected by means of a switch 3 with a diverging track Y which may, for example, comprise one end of a passing siding. The main track X is provided with track sections 1T, 4T, 5T, A5T, 6T, A6T and 9T, while the diverging track Y is provided with a track section 3bT, the switch 3 being located in the track section 4T of the main track. For convenience, the section A5T will at times be referred to as an approach section.

Each track section is provided with a track circuit comprising the usual track relay R and a track battery. The track relays R are each indicated as associated with their respective track sections by their distinguishing preceding exponents.

The reference characters B and C designate the positive and negative terminals respectively of a source of current not shown in the drawing.

The switch 3 is operated between its two extreme positions by means of a switch machine SM which is responsive to the polarity of the current supplied thereto, and which is controlled by a polarized switch control relay 3WR. The switch machine SM is preferably of the well-known dual control electric type, and may for example be similar to that described and claimed in an application for Letters Patent of the United States, Serial No. 148,706, filed by William C. McWhirter and Edwin G. Little on January 17, 1937, for Railway switch operating apparatus, now U. S. Letters Patent No. 2,183,164, granted Dec. 12, 1939.

The circuits for controlling the switch machine by the switch control relay 3WR will be readily understood from an inspection of the drawing, these circuits being so arranged that the switch machine will be deenergized, or will be supplied with current of normal or reverse polarity to move the switch to its normal or its reverse position, according as the switch control relay is deenergized, or is energized by current of normal or reverse relative polarity. As is usual, when the switch machine becomes deenergized it will remain in the position to which it was last moved and will retain the switch locked in this position.

The switch machine SM includes a suitable circuit controller comprising pole changing contacts 10 and 11, which contacts control the supply of current to a polarized indication relay KR in such manner that the polar relay will be energized by current of normal polarity when and only when the switch occupies its normal position and is properly locked in this position, and by current of reverse polarity when and only when the switch occupies its reverse position and is properly locked in this position. It follows, therefore, that whenever the switch becomes unlocked or is in transit relay KR will be deenergized.

The switch control relay 3WR is controlled over a circuit which includes front contacts GPS—1 and GPS—2 of a safety relay GPS, the front contacts 13 and 14 of track relay 4TR, and pole changing contacts 3WS—1 and 3WS—2 of a

switch stick relay 3WS. This circuit is so arranged that when relay GPS and track relay 4TR are both energized, the current supplied to relay 3WR will have normal or reverse relative polarity according as relay 3WS is then deenergized or energized, and it follows, therefore, that when relays GPS and 4TR are both energized the switch will be moved to its normal or its reverse position according as relay 3WS is deenergized or energized. This arrangement insures that if relay 3WS should become improperly deenergized for any reason, and the switch 3 does not already occupy its normal position, it will move to this position so that traffic can proceed along the main track past the switch without delay.

Traffic moving from left to right over stretch X, that is to say eastbound traffic, is governed by signals 3a, 5 and 9 located respectively at the entrance ends of sections 4T, 5T and 9T, while westbound traffic over this stretch is governed by signals 6 and 4a located respectively at the entrance ends of sections A5T and 4T. Traffic leaving the siding Y is governed by a signal 3b, while traffic entering the siding is governed by a signal 4b. These signals may be of any preferred type, but as here shown they are color light signals, the signals 3a, 4a, 5, 6 and 9 each being provided with a green lamp G, a yellow lamp Y and a red lamp R, and the signals 3b and 4b each being provided with a yellow lamp Y and a red lamp R.

The section A5T into which signal 6 governs the entrance of westbound traffic will preferably be so located with respect to the grade and curvature of the track as to allow the average train to maintain a speed in excess of a predetermined speed, for example, 30 miles per hour, for a predetermined distance past the signal, such for example as 550 feet.

A fouling post FP is preferably located at the left-hand end of section 3bT to indicate to an engineman the point at which he will start to enter section 3bT.

The signal 3a is controlled by a home relay 3aH, and a distant relay 3aD over circuits which will be obvious from an inspection of the drawing. These circuits are so arranged that the green light will become lit to display a proceed indication when these relays are both energized, the yellow lamp will become lit to display a caution indication when the distant relay 3aD is de-energized and the home relay 3aH is energized, and the red lamp R will become lit to display a stop indication when the home relay is deenergized.

The signal 3b is controlled by a home relay 3bH in such manner that the yellow or red lamp of this signal will be lighted to display a caution or stop aspect according as relay 3bH is energized or deenergized. The circuits for controlling this signal will also be obvious from an inspection of the drawing.

The signal 4b is controlled by a home relay 4bH in the same manner that signal 3b is controlled by the relay 3bH.

The signal 4a is controlled by a polarized home relay 4H and a slow releasing home repeater relay 4HP, the control circuits being so arranged that the green lamp G will be lighted when relay 4HP is energized and relay 4H is energized by current of normal polarity, the yellow lamp Y will be lighted when the relay 4HP is energized and the relay 4H is energized by current of reverse polarity, and the red lamp R will be lighted when the relay 4HP is deenergized. The energiz-

ing circuits for this signal will be readily apparent from an inspection of the drawing.

The signal 5 is controlled by a polarized home relay 5H and a slow releasing home repeater relay 5HP in the same manner that signal 4 is controlled by relays 4H and 4HP, and signal 6 is similarly controlled by relays 6H and 6HP.

The control relays and circuits controlled thereby for controlling signal 9 are not shown, but it will be readily understood that this latter signal is likewise controlled in a manner similar to signal 5.

The polarized relay 6H is controlled by track relays A5TR, 5TR and 4TR, and by a pole changing relay A4PC, over a circuit which includes a front contact 15 of track relay A5TR, a front contact 16 of track relay 5TR, a front contact 95 of track relay 4TR, and pole changing contacts 17 and 18 of relay A4PC. This circuit is so arranged that when track relays 5TR, A5TR and 4TR are all energized, relay 6H will be supplied with current of normal or reverse relative polarity, and will move its polar contacts to their normal or reverse positions, according as relay A4PC is then energized or deenergized.

Relay A4PC is controlled by relay 4H over a circuit which passes from terminal B through front contact 19 of relay 4H, normal polar contact 20 of relay 4H and the winding of relay A4PC to terminal C, and it will be apparent, therefore, that relay A4PC will be energized when and only when relay 4H is energized by current of normal relative polarity.

Relay 4H is controlled over a polarized circuit which is similar to that just described for relay 6H, only that portion of this circuit being shown which includes front contact 12 of the track relay 4TR. Inasmuch as the circuit for controlling relay 4H is similar to that for controlling relay 6H, it is deemed to be unnecessary to describe it further herein.

The relay 6H controls the repeater relay 6HP by virtue of a circuit which includes a front contact 18 of relay 6H, and it will be seen, therefore, that relay 6HP will be energized whenever relay 6H is energized.

Associated with signal 6 is the usual directional stick relay 6S, which latter relay is controlled jointly by the track relay A5TR and home repeater relay 6HP in accordance with well-known practice in such manner that this relay will become picked up when a westbound train enters section A5TR, and will subsequently be held in its picked up condition until the train which caused it to pick up clears section 5T, but will remain deenergized during movement of an eastbound train over track X. The pick-up circuit for relay 6S may be traced from terminal B through front contact 20-20a of relay 6HP, back contact 21 of relay A5TR and the winding of relay 6S to terminal C. This circuit will become closed only for the brief interval of time required for front contact 20-20a of relay 6HP to open after track relay A5TR becomes de-energized, it being obvious that the deenergization of track relay A5TR deenergizes relay 6H and hence relay 6HP. One stick circuit for relay 6S passes from battery B through back contact 22 of track relay A5TR, front contact 23 of stick relay 6S, and the winding of relay 6S to battery C, and another stick circuit for this relay passes from terminal B through back contact 20-20b of relay 6HP, front contact 23 of relay 6S, and the winding of relay 6S to terminal C. The function of the stick circuit including back contact 70

22 of relay A5TR is to prevent relay 6S from becoming deenergized during the interval of time which elapses between the opening of the pick-up circuit for relay 6S at front contact 28—20a of relay 6HP and the closing of the other stick circuit for relay 6S at back contact 20—20b of relay 6HP.

The relay 6S together with the track relays A5TR and 5TR control a time element relay TE over a circuit which passes from terminal B through front contact 26 of relay 6S, wire 27, the winding of relay TE, front contact 28 of relay 5TR, back contact 29 of relay A5TR and front contact 30 of relay 6S to terminal C. It will be seen, therefore, that whenever a westbound train enters section A5T and deenergizes track relay A5TR, the resultant picking up of stick relay 6S will complete the circuit for relay TE provided section 5T is then unoccupied, so that front contact 28 of track relay 5TR is closed.

The time element relay TE may be of any suitable type such for example as that described and claimed in an application for Letters Patent of the United States, Serial No. 732,857, filed by Branko Lazich and Harry E. Ashworth on June 28, 1934, for Electrical relays, now U. S. Letters Patent No. 2,172,828, granted Sept. 12, 1939, and is provided with a back contact 24 which is closed at all times when the relay is deenergized and which remains closed when the relay becomes energized until after the time interval for which the relay is set has expired, and with a time element contact 25 which is open when the relay is deenergized and which remains open after the relay becomes energized until after the expiration of the time interval for which the relay is set. The time interval for which the relay is set can readily be varied, and will be so adjusted that it will be greater than that required for a train to traverse section A5T if the average speed of the train exceeds a predetermined speed such for example as 30 miles per hour, whereby the relay TE will close its timing contact when and only when the speed of a train traversing section A5T is less than said predetermined speed.

Relay 5H is provided with an energizing circuit which passes from terminal B through front contact 31—31a of a repeater relay 9HP, front contact 32 of track relay A6TR, front contact 33 of track relay 6TR, front contact 34 of track relay A5TR, front contact 35 of track relay 5TR, the winding of relay 5H, common wire 5C and back contact 37—37b of a stick relay 9S to terminal C. Relay 5H is also provided with another energizing circuit which is similar to that just described except for the fact that this latter circuit includes a front contact 37—37a of relay 9S instead of back contact 31—31b of this relay, and a back contact 31—31b of relay 9HP instead of front contact 31—31a of this relay. These circuits are so arranged that when the circuit first traced is closed relay 5H will be supplied with current of normal polarity, whereas when the circuit last traced is closed relay 5H will then be supplied with current of reverse relative polarity.

The control circuits for the relays 9HP and 9S are not shown, but it will be readily understood that these circuits will be similar to those previously described for controlling relays 6HP and 6S.

The relay 5H controls the relay 5HP over a circuit which will be obvious from an inspection of the drawing in such manner that relay

5HP will be energized whenever relay 5H is energized.

Associated with signal 5 is an eastbound stick relay 5S which is controlled by the two track relays 4TR and 5TR and the track repeater relay 5 5HP in such manner that relay 5S will pick up during the interval required for relay 5HP to drop when an eastbound train enters section 5T and deenergizes track relay 5TR, and will subsequently remain stuck up until the train clears section 6T. The pick-up circuit for relay 5S passes from terminal B through front contact 5HP—20—20a of relay 5HP, back contact 5TR—21 of relay 5TR, back contact 4TR—92 of track relay 4TR, and the winding of relay 5S to terminal C. One stick circuit for relay 5S passes from terminal B through back contact 22 of relay 5TR, front contact 23 of relay 5S and the winding of relay 5S to terminal C, while another stick circuit for relay 5S passes from terminal B through back contact 5HP—20—20b of relay 5HP, front contact 23 of relay 5S and the winding of relay 5S to terminal C. The function of the one stick circuit is to maintain relay 5S energized during the interval between the opening of front contact 5HP—20—20a of relay 5HP and the closing of the back contact 5HP—20—20b of relay 5HP.

The home relay 5H also controls the distant relay 3AD over a circuit which passes from terminal B through front contact 5H—40 of relay 5H, normal polar contact 5H—41 of relay 5H and the winding of relay 3AD to terminal C. It will be obvious that this circuit will be closed only when relay 5H is energized in its normal direction, and it follows that when relay 5H becomes deenergized and causes the signal 5 to display a red or stop signal relay 3AD will also become deenergized and will cause signal 3 to display a yellow or caution signal. (40)

Associated with the signals 4a and 4b is a westbound stick relay 4S corresponding to the eastbound stick relays 5S associated with signal 5. The stick relay 4S is provided with two pick-up circuits one of which passes from terminal B through front contact 4HP—45—45a of relay 4HP, back contact 4TR—46 of track relay 4TR, back contact 5TR—11 of track relay 5TR and the winding of relay 4S to terminal C, and the other of which passes from terminal B through front contact 4bH—49 of relay 4bH, back contact 4TR—46 of track relay 4TR, back contact 5TR—11 of relay 5TR and the winding of relay 4S to terminal C. (45)

Relay 4S is also provided with two stick circuits, one of which passes from terminal B through back contact 4HP—45—45b of relay 4HP, back contact 4bH—48 of relay 4bH, front contact KR—50 of relay KR, front contact 51 of relay 4S and the winding of relay 4S to terminal C, and the other of which stick circuits passes from terminal B through back contact 4TR—47 of track relay 4TR, front contact KR—50 of relay KR, front contact 51 of relay 4S and the winding of relay 4S to terminal C. (55) The manner in which these pick-up and stick circuits control relay 4S will be made clear as the description proceeds.

The reference character 3bTPS designates a track repeater relay. This relay is provided with a pick-up circuit which includes front contact 52 of track relay 3bTR, and with a stick circuit which includes a front contact 53 of track relay 4TR and its own front contact 54. (60)

The switch stick relay 3WS is provided with (75)

one pick-up circuit which passes from terminal B through front contact 25 of time element relay TE, front contact 93 of relay GPS, and the winding of relay 3WS to terminal C. The relay 3WS is also provided with another pick-up circuit which passes from terminal B through front contact 92 of a slow releasing siding stick relay 3bS, front contact 93 of relay GPS, and the winding of relay 3WS to terminal C.

- 10 The siding stick relay 3bS is provided with a pick-up circuit which passes from terminal B through front contact 3bTPS—55 of relay 3bTPS, back contact 3bTR—56 of relay 3bTR, contact 4HP—57 of relay 4HP and contact 4S—59 of relay 4S in multiple, contact 5HP—58 of relay 5HP and contact 5S—60 of relay 5S in multiple, and the winding of relay 3bS to terminal C. This relay is also provided with a stick circuit which passes from terminal B through back contact 90 of relay 3WS, front contact 91 of relay 3bS, and the winding of relay 3bS to terminal C.

Relay 3WS is further provided with a stick circuit which passes from terminal B through front contact 62 of track relay 4TR, front contact 61 of relay 3WS, and the winding of relay 3WS to terminal C.

Relay 3aH is provided with an energizing circuit which passes from terminal B through contact 65 of a time release T, back contact 3bS—94 of relay 3bS, back contact 24 of time element relay TE, front contact 66 of track relay 4TR, front contact 5TR—67 of track relay 5TR, front contact 68 of relay KR, normal polar contact 69—69a of polar relay KR, front contact 70 of track relay 3bTR, back contact 3WS—71 of relay 3WS, and the winding of relay 3aH to terminal C. It will be seen, therefore, that relay 3aH will become energized when and only when time release T is in its normal position, relay 3bS is deenergized, time element relay TE is deenergized, sections 3bT, 4T and 5T are all unoccupied, and the switch occupies its normal position and is locked in this position so that the KR relay is energized in its normal direction.

45 The time release T may be of any desired type, but as here shown it is a clockwork time release similar to that shown and described in Letters Patent of the United States No. 1,989,522, granted to William C. McWhirter on January 29, 1935, for Time governed circuit controlling mechanisms. Since the time release T is similar to the time release shown in the said McWhirter patent, it is believed that for purposes of the present disclosure it is sufficient to state that this release is provided, in addition to the contact 65, which contact is a normally closed contact, with a normally open contact 80 to be referred to herein-after, and that, when the release is set into operation the contact 65 immediately becomes opened, and the contact 80 remains opened until the expiration of a predetermined time interval. After the release has been operated to open the contact 65 and close the contact 80, the contact 65 will subsequently remain opened and the contact 80 will remain closed until the time release is manually restored to its normal condition.

Relay 3bH is provided with an energizing circuit which passes from terminal B through normally closed contact 65 of time release T, back contact 3bS—94 of relay 3bS, back contact 24 of time element relay TE, front contact 69 of track relay 4TR, back contact 5TR—67 of track relay 5TR, front contact 68 of relay KR, reverse polar contact 69—69b of relay KR, front contact

3WS—72 of relay 3WS, and the winding of relay 3bH to terminal C. It will be obvious, therefore, that relay 3bH will be energized when and only when time release T occupies its normal position, relay 3bS is deenergized, time element relay TE is deenergized, track sections 4TR and 5TR are both unoccupied, the switch is locked in its normal position, and the switch stick relay 3WS is energized.

10 Relay 4HP is provided with an energizing circuit which passes from terminal B through normally closed contact 65 of the time release T, back contact 3bS—94 of relay 3bS, back contact 24 of time element relay TE, front contact 66 of track relay 4TR, front contact 73 of track relay 15 3bTR, front contact 74 of relay KR, normal polar contact 75—75a of relay KR, front contact 4H—76 of relay 4H, back contact 3WS—71 of relay 3WS, and the winding of relay 4HP to terminal C. It follows that relay 4HP will be 20 energized when and only when time release T occupies its normal condition, relay 3bS is deenergized, time element relay TE is deenergized, track relays 4TR and 3bTR are both energized indicating that the associated sections are unoccupied, relay KR is energized in its normal direction, home relay 4H is energized, and the switch stick relay 3WS is deenergized.

25 Relay 4bH is provided with an energizing circuit which is similar to that just described for 30 relay 4HP with the exception that this latter circuit includes reverse polar contact 75—75b of polar relay KR and front contact 3WS—78 of relay 3WS in place of normal polar contact 75—75a of relay KR, front contact 4H—76 of relay 4H, and back contact 3WS—71 of relay 3WS. It will be seen, therefore, that this relay will be energized when and only when time release T occupies its normal condition, relay 3bS is deenergized, time element relay TE is 40 deenergized, track section 4T is unoccupied so that track relay 4TR is energized, track section 3bTR is unoccupied, the switch occupies its reverse position so that relay KR is energized in its reverse direction, and the switch stick relay 3WS 45 is energized.

50 The relay GPS is provided with a first pick-up circuit which is closed when and only when relays 3bH, 4bH, 4HP and 3aH are all deenergized, and which passes from terminal B through back contact 3bH—83 of relay 3bH, back contact 34 of relay 4bH, back contact 4HP—85 of relay 4HP, back contact 3aH—86 of relay 3aH, and the winding of relay GPS to terminal C. Relay 55 GPS is also provided with another pick-up circuit which includes the back normally open contact 80 of time release T and the winding of relay GPS as will be obvious from an inspection of the drawing.

60 In explaining the operation of the system as a whole, I shall first assume that all parts are in their normal positions in which they are shown in the drawing and that a train desiring to enter the siding Y enters section 9T.

65 The entrance of the train into section 9T will deenergize track relay 9TR which latter relay, in turn, will cause the relay 9HP to become deenergized and interrupt the circuit for relay 5H. Relay 5H will therefore become deenergized and 70 will deenergize relay 5HP, thereby causing signal 5, which previously displayed a proceed indication, to now display a stop indication. The deenergization of relay 5HP will also interrupt at its front contact 5H—40 the circuit for the dis- 75

tant relay 3aD, and will thus cause signal 3a to display a caution aspect.

When the train enters sections A6T and 6T, respectively, track relays A6TR and 6TR will become deenergized, and will thus hold the circuit for relay 5H open, so that when the train passes out of section 9T, signal 5 will continue to display a stop aspect and signal 3a will continue to display a caution aspect.

10 When the train enters section A5T it will reduce its speed to such a value that the time required for it to traverse this section will be greater than that required for time element relay TE to operate its time contacts 24 and 25, 15 and the train will keep its speed at or below this value during the entire time it is traversing section A5T.

The entrance of the train into section A5T will of course deenergize track relay A5TR, which 20 will cause signals 5 and 3a to continue to display caution and stop aspects, respectively. The deenergization of track relay A5TR will also interrupt at its front contact 15 the circuit for relay 6H, and relay 6H will therefore become de- 25 energized and will deenergize relay 6HP, thereby causing signal 6 to display a stop aspect.

The deenergization of relay A5TR will further complete the pick-up circuit for stick relay 6S during the interval required for relay 6HP, which 30 as was previously pointed out is a slow releasing relay, to open its front contact 20-20a, and, as soon as relay 6S picks up, its stick circuit including back contact 22 of track relay A5TR will become closed, so that when front contact 20- 35 20a of relay 6HP finally opens, relay 6S will remain energized. The releasing of the armature of relay 6HP will also complete the other stick circuit for relay 6S, and it will be apparent, therefore, that relay 6S will remain energized even 40 though the train now completely passes out of section A5T and causes relay A5TR to again pick up, thus interrupting the one stick circuit for relay 6S including the front contact 22 of track relay A5TR.

45 The picking up of relay 6S completes at its front contacts 26 and 30 the pick-up circuit for time element relay TE, and since the time required for the train to traverse section A5T will be longer than the pick-up time for relay TE, relay TE will pick up its armature while the train is traversing section A5T, and will open its back contact 24 and close its front contact 25.

50 The opening of back contact 24 of relay TE interrupts the circuits for relays 3aH, 3bH, 4HP and 4bH, thereby causing relays 3aH and 4HP to become deenergized, and hence insuring that signals 3a, 3b, 4a and 4b will now all display stop aspects.

55 The deenergization of relays 3aH and 4HP also completes the pick-up circuit for relay GPS, and this relay therefore picks up its armature and closes its front contacts GPS-1, GPS-2 and 93. The closing of contacts GPS-1 and GPS-2, in turn, will complete the normal energizing circuit for relay 3WR, and this relay will therefore pick up its neutral armature, and thus cause current of normal polarity to be supplied to switch machine SM. The application of current to the switch machine SM under these conditions, however, will have no effect on the switch since the switch already occupies its normal position.

70 The closing of front contact 93 of relay GPS completes the previously traced pick-up circuit for relay 3WS including front contact 25 of time

element relay TE, and relay 3WS therefore picks up its armature and closes its stick circuit including its front contact 61 and front contact 62 of track relay 4TR. The closing of the stick circuit for relay 3WS insures that this relay will remain energized when the circuit for time element relay TE subsequently becomes opened at front contact 28 of track relay 5TR due to the entrance of the train into track section 5T.

75 As soon as relay 3WS becomes energized, it 10 reverses the polarity of the current supplied to relay 3WR which causes the switch to move to its reverse position. This movement of the switch, in turn, reverses the polarity of the current supplied to relay KR, and this relay then reverses 15 its polar armature, thereby causing relays 3bH and 4bH to pick up and hence causing signals 3b and 4b to display clear aspects.

The picking up of relays 3bH and 4bH also 20 interrupts the energizing circuit for relay GPS, which relay now becomes deenergized and de-energizes relay 3WR, to thereby prevent any further movement of the switch under these conditions.

25 It should here be noted that in order for relay 3WR to become energized in its reverse direction and reverse the switch, it is necessary for relay GPS to be energized, and this relay will not be energized unless relays 3bH, 4bH, 4HP and 3aH are all deenergized, thus insuring that 30 the switch will only be reversed when all signals governing traffic over it occupy their stop positions.

35 The train may now enter section 4T. When the train does this, track relay 4TR will of course become deenergized and will interrupt at its front contact 66 the circuits for relays 3bH and 4bH, which will cause signals 3b and 4b to again display stop aspects, and relay GPS to again become energized. The energization of relay GPS 40 under these conditions, however, will not complete the circuit for relay 3WR since this circuit will then be open at front contacts 13 and 14 of track relay 4TR.

45 The deenergization of track relay 4TR will also maintain the circuit for relay 6H open, so that this relay and relay 6HP will remain deenergized, thereby causing signal 6 to continue to display a stop aspect.

50 The deenergization of relay 4TR will further interrupt at its front contact 62 the stick circuit for relay 3WS which will cause this relay to become deenergized.

55 When the train enters section 3bT, the resultant deenergization of track relay 3bTR will cause the pick-up circuit for relay 3bTPS to become opened at front contact 52 of relay 3bTR, and since the stick circuit for relay 3bTPS will then be open at front contact 53 of relay 4TR, relay 3bTPS will become deenergized. The deenergization of relay 3bTPS under these conditions, however, will have no effect on the remainder of the apparatus.

60 As soon as the train passes out of section 4T, and causes relay 4TR to pick up, relay 3WR will again be supplied with current of normal polarity, which will cause the switch to return to its normal position. When the switch returns to its normal position, relay KR will again become energized in its normal direction.

65 The picking up of relay 4TR will also complete the circuit for relay 6H, thereby causing this relay to pick up and complete the pick-up circuit of relay 6HP. Relay 6HP will therefore also pick up and cause signal 6 to display a clear aspect.

When the train clears section 3bT, the resulting picking up of track relay 3bTR will cause relays 3bTPS, 3aH and 4HP to pick up, whereupon signals 3a and 4a will display clear aspects and signals 3b and 4b will display stop aspects. All parts will then be restored to the positions in which they are shown in the drawing.

I shall now assume that there are no trains approaching the switch 3 in either direction on the main track X, and that an eastbound train in the siding Y wishes to proceed. The train upon entering section 3bT will deenergize track relay 3bTR, which will interrupt the circuits for relays 3aH and 4HP, thereby causing signals 3a and 4a to display stop aspects.

The deenergization of track relay 3bTR also completes, during the brief interval of time required for relay 4HP to open its contact 4HP-51 after it becomes deenergized, the pick-up circuit for relay 3bS, whereupon this latter relay picks up and closes its stick circuit including back contact 90 of relay 3WS.

The picking up of relay 3bS opens the circuits for all four signal control relays 3aH, 3bH, 4HP and 4bH, thereby insuring that these signals will continue to display stop aspects under these conditions.

As soon as relays 3aH and 4HP become deenergized, the pick-up circuit for relay GPS becomes closed, and this relay therefore becomes energized and completes the pick-up circuit of relay 3WS including front contact 92 of relay 3bS.

The picking up of relay 3WS, in turn, completes at its front contact 61 its stick circuit, and interrupts at its back contact 90 the stick circuit for relay 3bS. Relay 3bS thereupon becomes deenergized and interrupts the pick-up circuit which caused relay 3WS to become energized. Relay 3WS remains energized, however, by virtue of its stick circuit.

The picking up of relay 3WS also reverses the polarity of the current supplied to relay 3WR, and this relay therefore reverses its polar armature, thereby causing the switch machine to move the switch 3 to its reverse position. As soon as the switch reaches its reverse position, relay KR becomes energized in its reverse direction and completes the circuits for relays 3bH and 4bH. These relays therefore become energized and interrupt the circuit over which relay GPS was previously energized, as well as complete the circuits for energizing the yellow lamps of signals 3b and 4b. The deenergization of relay GPS locks the switch in its reversed position, and since the signals 3b and 4b are now displaying their least restrictive indication, the train may now proceed.

When the train enters section 4T, track relay 4TR becomes deenergized and interrupts at its front contact 95 the circuit for relay 6H. Relay 6H thereupon becomes deenergized and deenergizes relay 6HP, thereby causing signal 6 to display a stop aspect.

The deenergization of track relay 4TR also interrupts at its front contact 66 the circuits for relays 3bH and 4bH, thereby causing signals 3a and 4b to display stop aspects and causing relay GPS to again become energized.

The deenergization of track relay 4TR further interrupts the stick circuit for relay 3WS so that this relay now becomes deenergized. The deenergization of this relay, however, does not reverse the polarity of the current supplied to relay 3WR because its circuit will then be open at front contacts 13 and 14 of relay 4TR.

The deenergization of relay 4TR further interrupts the stick circuit for relay 3bTPS which now becomes deenergized.

When the train enters section 5T, the resultant deenergization of track relay 5TR causes relay 5H, and hence relay 5HP to become deenergized, thereby causing signal 5 which previously displayed a clear aspect to now display a stop aspect.

The deenergization of relay 5TR also maintains the circuit for relay 6H open, interrupts at its front contact 67 the circuit for relay 3bH, and completes at its back contact 21 the circuit for stick relay 5S. Relay 5S thereupon becomes energized and completes its stick circuit including back contact 22 of track relay 5TR to subsequently maintain it energized as long as the train remains in section 5T. The energization of relay 5S under these conditions has no immediate effect on the remainder of the apparatus, the function of the relay 5S being to permit following train moves in accordance with standard absolute permissive block signaling practice.

When the train clears section 3bT, track relay 3bTR will pick up and reestablish the pick-up circuit for relay 3bTPS, whereupon relay 3bTPS will again become energized.

When the train clears section 4T, the resultant reenergization of track relay 4TR will cause it to close its front contacts 13 and 14. When this happens, the circuits for relays 3aH and 3bH 30 will both be open at contact 5TR-67 of track relay 5TR, the circuit for relay 4HP will be open at normal polar contact 15-15a of relay KR, and the circuit for relay 4bH will be open at front contact 3WS-78 of relay 3WS, so that relays 3aH, 3bH, 4HP and 4bH will all be deenergized and relay GPS will be energized. Relay 3WR will therefore now be supplied with current of reverse polarity and will cause the switch machine SM to become energized and restore the switch 3 to its normal position. As soon as the switch reaches its normal position, relay KR will become energized in its normal direction, and will complete the circuit for relay 4HP, thereby causing signal 4a to display a clear aspect.

From this point on the operation of the apparatus will be in accordance with standard practice in absolute permissive block signaling systems, and since such systems are well known, it is believed that this operation will be readily understood by those skilled in the art without further detailed description.

I shall now assume that an eastbound train which is waiting in the siding Y to the left of the fouling post FP desires to enter the main track X as soon as a westbound train which is approaching the switch from a point to the left of the section 9T passes the switch.

Under these conditions, the operation of the apparatus will be similar to that previously described for a westbound train desiring to enter the siding Y until the train passes signal 6. When this happens, if the train is not already traveling at a speed of more than 30 miles per hour, it will increase its speed, and will subsequently maintain its speed at a sufficiently high value so that time element relay TE will not pick up while the train is traversing section A5T. As a result, relay 3WS will remain deenergized and cause the switch to be held in its normal position.

When the train enters section 5T, the resultant deenergization of track relay 5TR will interrupt at its front contact 5TR-67 the circuit for relay 3aH, and this relay will therefore become deener-

gized and will cause signal 3a to display a stop aspect.

The westbound train upon entering section 4T will deenergize track relay 4TR, whereupon relay 5HP will become deenergized and cause signal 4a to display a stop aspect. The deenergization of relay 4HP, in turn, will complete the circuit for relay GPS which will then pick up, but the picking up of this relay will have no effect on the remainder of the apparatus since the circuit for relay 3WR will then be open at front contacts 13 and 14 of track relay 4TR.

The deenergization of track relay 4TR will also cause stick relay 4S to become energized since track relay 5TR will then still be deenergized, and as a result relay 4S will pick up and close both its stick circuit including back contact 41 of track relay 4TR and its stick circuit including back contact 4HP—45 of relay 4HP.

20 When the westbound train enters section 1T, track relay 1TR will become deenergized and will interrupt the circuit for relay 4H, which latter relay, in turn, will become deenergized and will deenergize relay A4PC. Relay A4PC upon becoming deenergized will reverse its pole changing contacts 17 and 18, and as soon as the train clears section 4T to thus cause track relay 4TR to pick up, relay 6H will pick up and will cause relay 6HP to pick up, thereby causing signal 6 to display a caution aspect.

30 The picking up of relay 4TR will also complete at its front contact 66 the circuit for relay 3aH, whereupon this relay will pick up and will cause signal 3b to display a proceed at slow speed aspect. The circuit for relay 4HP, however, will now be open at contact 4H—16 of relay 4H and relay 4HP will therefore remain deenergized to retain the stick circuit for stick relay 4S closed.

35 The eastbound train which up until this time remained to the left of the fouling post FP may now proceed. As soon as the train enters section 3bT, track relay 3bTR will become deenergized. The deenergization of this relay will deenergize relay 3aH and will thus cause signal 3a to display a stop aspect and relay GPS to become energized.

40 The deenergization of track relay 3bTR will also complete the pick-up circuit for relay 3bS including contact 4S—59 of relay 4S, and relay 3bS will therefore pick up and complete its stick circuit.

45 When relay 3bS picks up, the pick-up circuit for relay 3WS will become closed, and since relay GPS is then energized, relay 3WR will be supplied with current of reverse polarity and will cause switch 3 to reverse. As soon as switch 3 reverses, polar relay KR will reverse and will cause signals 3b and 4b to clear. The reversal of relay KR will also interrupt at its front contact KR—50 both stick circuits for relay 4S, which 50 relay will then become deenergized. From this point on the operation of the apparatus will be identical with that previously described when an eastbound train which was in the siding traversed the stretch of track shown in the drawing.

55 When an eastbound train traverses the stretch of track X, the apparatus will function in a manner similar to standard practice in absolute permissive block signaling systems, and since this operation is in accordance with standard practice, it is believed to be unnecessary to describe it in detail herein.

60 It should be pointed out that one reason for including front contact 50 of relay KR in the stick circuit for relay 4S is to prevent relay 4S from being held up after it is picked up due to

a westbound train on the main track clearing section 4T if in the meanwhile an eastbound train on the siding enters section 3bT, and thereby causes the switch to reverse.

65 Although I have herein shown and described only one form of railway traffic controlling apparatus embodying my invention, it is understood that various changes and modifications may be made therein within the scope of the appended claims without departing from the spirit and scope of my invention.

70 Having thus described my invention, what I claim is:

1. In combination, a stretch of railway track divided into sections including an approach section, a siding connected by means of a switch with said stretch in rear of said approach section for trains approaching said switch in a facing point direction, a time element relay including a back contact which becomes opened and a front contact which becomes closed when and only when said relay remains energized for a predetermined time interval, signals for governing traffic over said switch controlled in part by traffic conditions in the vicinity of said switch and in part by said back contact, means for energizing said time element relay while a train is traversing said approach section toward said switch and means effective when the front contact of said time element relay is operated for reversing said switch if said signals then occupy their stop positions.

2. In combination, a stretch of railway track including a detector section having a switch located therein and an approach section, a time element relay having a back contact which becomes opened and a front contact which becomes closed after the relay has been energized for a predetermined time interval, means for energizing said time element relay while a train approaching said switch is traversing said approach section, signals for governing traffic movements over said switch, means for clearing said signals to permit traffic to proceed over said switch if and only if said back contact is closed and said detector section is unoccupied, and means for reversing said switch when said front contact becomes closed provided said signals are then displaying stop aspects.

3. In combination, a stretch of railway track including a detector section having a switch located therein and an approach section, a time element relay having a back contact which becomes opened and a front contact which becomes closed after the relay has been energized for a predetermined time interval, means for energizing said time element relay while a train approaching said switch is traversing said approach section, automatic signals for governing traffic over said switch controlled in part by said back contact, and means controlled by said front contact for reversing said switch.

4. In combination, a stretch of railway track including a detector section having a switch located therein and an approach section, a time element relay having a back contact which becomes opened and a front contact which becomes closed after the relay has been energized for a predetermined time interval, means for energizing said time element relay while a train approaching said switch is traversing said approach section, automatic signals for governing traffic over said switch controlled in part by said back contact, a switch stick relay, means for energizing said stick relay when said front contact be-

comes closed and for subsequently maintaining it energized until a train enters said detector section, and means controlled by said switch stick relay for controlling the position of said switch.

5. In combination, a stretch of railway track including a detector section having a switch located therein and an approach section, a time element relay having a back contact which becomes opened and a front contact which becomes opened after the relay has been energized for a predetermined time interval, means for energizing said time element relay while a train approaching said switch is traversing said approach section, automatic signals for governing traffic over said switch controlled in part by said back contact, a switch stick relay, means for energizing said stick relay when said front contact becomes closed, a track relay for said detector section, a stick circuit for said stick relay including a front contact of said track relay, and means effective when said switch stick relay becomes energized for reversing said switch.

6. In combination, a stretch of railway track including a detector section having a switch located therein and an approach section, a time element relay having a back contact which becomes opened and a time contact which becomes closed after the relay has been energized for a predetermined time interval, means for energizing said time element relay while a train approaching said switch is traversing said approach section, automatic signals for governing traffic movements over said switch, means effective when said back contact becomes opened for causing said signals to display stop indications, and means controlled by said time contact for reversing said switch if said detector section is unoccupied when said time contact becomes closed.

7. In combination, a stretch of railway track including a detector section having a switch located therein and an approach section, a time element relay having a back contact which becomes opened and a front contact which becomes closed after the relay has been energized for a predetermined time interval, means for energizing said time element relay while a train approaching said switch is traversing said approach section, automatic signals for governing

traffic movements over said switch, means for causing said signals to display stop aspects when said back contact becomes opened, a safety relay, means for energizing said safety relay when said signals occupy their stop positions, a switch stick relay, a pick-up circuit for said switch stick relay including said front contact and a front contact of said safety relay, a track relay for said detector section, a stick circuit for said switch stick relay including its own front contact and a front contact of said track relay, and means effective when said track and safety relays are both energized for moving said switch to its normal or reverse position according as said switch stick relay is then energized or deenergized.

8. In combination, a stretch of railway track including a detector section having a switch located therein and an approach section, a time release including a normally closed contact which becomes opened immediately when said time release is set into operation and a time contact which becomes closed at the expiration of a measured time interval after said release is set into operation, automatic signals for governing traffic movements over said switch, a time element relay including a back contact which becomes opened and a front contact which becomes closed at the expiration of a predetermined time interval after said time element relay becomes energized, means for causing said signals to display stop aspects whenever said normally closed contact or said back contact becomes opened, means for energizing said time element relay while a train approaching said switch is traversing said approach section, a safety relay, a switch stick relay, means for energizing said switch stick relay when said safety relay becomes energized if said front contact is then closed and for subsequently maintaining said stick relay energized until a train enters said detector section, means for energizing said safety relay when said signals are displaying stop aspects, and means for reversing said switch when said switch stick relay becomes energized if said safety relay is then energized and said detector section is unoccupied.

MILLS R. SNYDER.
